(57) CLAIM

The ornamental design for a display screen or portion thereof with an animated graphical user interface, as shown and described.

DESCRIPTION

FIG. 1 illustrates a front view of a display screen or portion thereof with an animated graphical user interface (GUI) showing a first image in the sequence showing the new design;

FIG. 2 illustrates a second image thereof;

FIG. 3 illustrates a third image thereof;

FIG. 4 illustrates a fourth image thereof;

FIG. 5 illustrates a fifth image thereof;

FIG. 6 illustrates a sixth image thereof;

FIG. 7 illustrates a seventh image thereof;

FIG. 8 illustrates an eighth image thereof;

FIG. 9 illustrates a ninth image depicted thereof; and,

FIG. 10 illustrates a tenth image thereof.

The rectangular dot-dash broken-line perimeter illustrates a display screen. The dashed broken lines outside this perimeter illustrate portions of an electronic device. The dashed broken lines within this perimeter illustrate portions of a graphical user interface. The broken lines form no part of the claimed design.

The appearance of the animated images sequentially transitions between the images shown in FIG. 1–10. The process or period in which one image transitions to another forms no part of the claimed ornamental design.
